UNITED STATES PATENT OFFICE

2,046,119

UNIVERSAL TELEPHONE REPEATER

William E. Harding, Indianapolis, Ind.

Application September 16, 1933, Serial No. 689,731

25 Claims. (Cl. 179—170)

The invention relates to telephone repeaters, and more especially to repeaters required in attenuated or long circuits in which it is necessary to amplify the voice currents carried by such circuits at intermediate points; and consists substantially in the construction and arrangement of parts disclosed in the accompanying drawings and pointed out more particularly in the claims.

It is a general object of the invention to provide an amplifying telephone repeater in which the usual or conventional artificial line is not required.

It is a primary object to provide a telephone repeater, which when considered from either end of same comprises a parallel-input E. M. F.-neutralizing circuit; an independent load-balancing circuit; a parallel-line "output" load-dividing circuit; an unbalance compensating circuit, and a vernier balancing circuit.

The above and other objects are attained by the structure illustrated in the accompanying drawings, of which:

Figure 1 is a diagram of the invention as a whole; and

Figure 2 is an enlarged and modified portion of Fig. 1.

Similar characters of reference designate similar parts throughout the different views.

Input and output balance

This repeater is universal to all telephone circuits, and dispenses with the usual artificial line, amplifying the power from the incoming line 1A to the outgoing line 1, turning to line 1, not only the usual power which would go to the line 1 in present repeaters, but the power ordinarily lost in an artificial line, in addition. This is accomplished by means of the parallel-line output load-dividing circuit 2; the load presented to output currents being equally divided across the "zero" points 3, as will be understood, of the independent load-balancing circuit 4, comprised in part by two transformers 5, one on each side, 6—7, of said points of zero output potential, and consisting of windings 8, 9, 10, 11 and 12, 13, 14, 15 respectively; the line windings 14 and 10 of which are in the aforesaid circuit 2, connected in series with the line 1. Parallel to impedance 16 and winding 14 are two other windings 11 and 15, one in each of the two said transformers 5, which are also in series with the line 1 and winding 10, but which are made to neutralize each other with respect to output currents, as will be understood. Thus the series-parallel circuit 2 is so connected as to evenly divide the output load between transformers 5; the output currents generated in windings 14 and 10 respectively in said transformers, being in the same direction and adding; the E. M. F. of such currents being equalized by the manually adjusted line dividing-impedance 16;

the output E. M. F. of windings 11 and 15 mutually opposing and neutralizing.

The windings 10, 11, 14 and 15 are series-parallel connected to the line 1, by which arrangement the output E. M. F. of winding 11 exactly opposes the output E. M. F. of winding 15; windings 11 and 15 being differentially connected together and having series relation in the line 1.

The input currents from the line 1 traverse the parallel circuits 2 in such manner as to neutralize windings 14 and 15, traversing primary windings 14 and 15 in opposing inductive directions in that transformer in one half 21 of the load-balancing circuit 4, traversing primary windings 10 and 11 in series, thus generating input E. M. F. in winding 8 in one half 20 of the independent load-balancing circuit 4 including the input transformer 22, thence to the first audio tube 23, thence through the repeater as a whole to the other associated line 1A which is balanced in exactly the same manner as above described. Thus far it should be clear that the repeater is balanced with regard to "output" currents and that only one side of the independent load-balancing circuit 4 is excited by input currents from the line 1. Reflective counter-E. M. F. from the line 1 is minimized by means of a third and compensating circuit 24, comprised of windings 8 and 12, in each of the aforesaid transformers and in series with variable impedance 25.

These two windings 8 and 12 are differentially connected and therefore neutralize each other with reference to output currents to the line 1, thus causing no loss of output E. M. F. But one 35 of these windings 8, being in the transformer in which the input currents add in windings 10 and 11, as above described, generates input currents from the line 1 (including reflective counter E. M. F.) through the other winding 12 in the other transformer in which input currents from the line 1 are made to neutralize in windings 14 and 15; thus generating input currents in winding 13 in the other half 21 of the independent load-balancing circuit 4.

In practice therefore, the variable impedance 25 is used, compromising output balance, output reaction and input volume within the scope of practicability.

A repeating coil 26 may be used across points 50 27 and 28 of circuit 24 with adjustable resistances at 25 and 29 as shown in Fig. 2, not altering the uses of circuit 24.

The output power balance in the two transformers 5, comprised in part of windings 10 and 11, and 14 and 15 respectively, has been described to indicate the even division of the line load between the two transformers 5, in windings 10 and 14 respectively; the power of winding 14 adding to that of winding 10.

It will be obvious that the power generated in the two line windings 14 and 10 from the output primary windings 30 and 31 of the separate power transformer comprised of windings 30, 31, 5 32 and 33, and flowing through windings 9 and 13 of the two balancing transformers 5 in series, having traversed secondary windings 14 and 10 in an upward direction on the drawings goes to the line on one side 34 and back on the other 10 side of the line to point 17; and that to evenly divide the line load in windings 14 and 10 therefore, the adjustable dividing resistance 16 must be adjusted to the value of the impedance of the line 1 thus neutralizing windings 11 and 15 to 15 output current, and windings 14 and 15 to input currents through parallel circuit 2 resistance 16 being increased or decreased according as the line resistance increases or decreases, to maintain the absolute balance of circuit 2.

20

The unbalance-compensating circuit

But repeater unbalances due to line changes, are prevented in this repeater because of the presence of the compensating circuit 24, in which 25 there is no current flow nor output power dissipation when the circuit 2 is balanced, but in which there is current flow due to line changes, increasing or decreasing line load or impedance; for when the line resistance increases, for example, there is less load in winding 10 than in winding 14, thus increasing the impedance of primary winding 9 over that of primary winding 13; windings 14 and 15 having the greater load, since dividing impedance 16 does not change except 30 manually. The increase of line impedance in winding 10 is effective in windings 8 and 12 of the compensating circuit; the greater load in one transformer over that of the other causing increased E. M. F. in winding 8 and consequent 35 current flow from winding 8 through winding 12 and thus shifting the unbalance from the line to the compensating circuit and preventing the unbalance ordinarily due to such line changes; the current flow from winding 8 through winding 14 40 balancing the E. M. F. of winding 13 against that of winding 9; the reverse action occurring in case of decreased line impedance.

Vernier balance

50 That part of the independent load-balancing circuit 4 composed of the variable resistance or potentiometer 37 and winding 38 of the input transformer 22 is used as a variable or vernier adjustment to balance outgoing or output voltage in the primary circuit 39 and 38 to obtain 55 absolute zero potential of output currents at points 3 and 3'; or to correct slight unbalances in the windings comprising the circuit 4, including the center-tapped inductance 40 shown with 60 bridged condenser 41; condensers 41 and 42 being used to by-pass slight unbalanced output voltage over the zero points 3 and 3' of the input circuit. Winding 38 of the input transformer 22 receives 65 current from the potentiometer 37 in an opposite or opposing direction to that in winding 39 of the input transformer.

Amplifier—Gain control

Windings 30, 31 32 and 33 are all in one transformer, the source of outgoing or output power; the circuit being actuated by amplifying tube 43 and its associated preceding equipment. Windings 30 and 31, and 9 and 13 are primary with reference to output currents; windings 10, 11, 14 75 and 15 are primary with reference to input cur-

rents; windings 8, 12, 9, 13, 32 and 33 being secondary in both cases.

The volume output of either half of the repeater is controlled by decibel-calibrated gain-potentiometers 44 and 44A.

The plate circuit composed of windings 30 and 31 is free of shunting condensers and impedances, thus causing no loss to input currents from line 1 through windings 10, 11, 14 and 15, and 32, 9, 13 and 33.

A variable impedance may be used at point 45 thus making the repeater balance more immune to line changes.

This however reduces input amplitude due to the presence of resistance 45 in the parallel circuit with windings 15 and 11, thus minimizing the neutralization of windings 14 and 15 with reference to input currents, and therefore requires the removal of output shunt 42.

The connections between windings 11 and 15 20 via point 45 may be made at the inductance taps shown as 46 and 47, and resistance 16 excluded if desired; the balance of circuit 2 being obtained with, or without inductance taps, and with or without resistance 16, or by the use of both 25 said means. Also the same result is obtained with variable resistance or inductance at point 45 in addition to resistance 16.

Parallel output load-dividing circuit

30

Referring to the functions and balance of the parallel line circuit 2, the operation is best illustrated by referring to windings 10, 11, 14 and 15 in which the output power is equally divided; the potential generated in each winding being, 35 let us say, three volts.

It is seen that the E. M. F. generated in winding 10 traverses the line 1 from point 34 to point 17 of the parallel circuit 2, where it would divide; two volts going via 14 to point 18, and one volt 40 via 15 and 11 to point 18; the one volt going via 15 and 11 from point 17 being in the opposite direction to the E. M. F. being generated in winding 15 and adding to that generated in winding 11.

The E. M. F. of three volts generated in winding 14 traverses the parallel circuit via 16 to point 18 where it would divide; two volts going via 10 and line 1 from point 19 to point 17, and one volt going via 11 and 15 of the parallel circuit 2 to point 17; the one volt going via 11 and 15 being in the opposite direction to the E. M. F. being generated in winding 15 and adding to that generated in winding 11; thus neutralizing the one volt from 10 through 15 and 11 from point 17 to point 18.

Actually, the E. M. F. of 10 and 14 does not so divide, since the E. M. F. of 10 is of the same polarity and potential at point 17 as that of 14 at point 18; the E. M. F. of 11 being of the same potential and polarity at point 18 as that of 15 50 at point 17, thus neutralizing windings 11 and 15; the impedance of 16 and that of the line 1 being equal.

Windings 15 and 11 are also directly in the circuit of line 1 between points 18 and 17, but 65 exactly neutralize each other in said line, with reference to output E. M. F., windings 15 and 11 being differentially connected.

Independent load-balancing circuit

70

Thus it is clear that the repeater is balanced; the E. M. F. of 15 being exactly balanced by the E. M. F. of 11, both in the parallel circuit 2 and in the line proper; windings 14 and 10 adding in the line, equally dividing the line load between 75

secondary windings 14 and 10, and between primary windings 13 and 9 of the load-balancing circuit 4; balancing impedance being controlled at 40 regardless of said load. It is seen that if line 1 is opened, winding 10 becomes ineffective, in which case there would be combined E. M. F. from windings 15 and 14, through winding 11 from point 18, being opposed only by the E. M. F. of winding 11; therefore the dividing impedance is provided at 16 to adjust for voltage drop through line 1 in practice to establish the balance of circuit 2; the same voltage proportion being maintained, but at any required value determined by the lines connected to the repeater.

15   *Input voice currents from line*

"Input" currents from line 1 through 10, 11, 14 and 15, function differently than do the output currents. In observing the other half of the repeater, input E. M. F. from line 1A enters the repeater at point 17A, dividing non-inductively through windings 14A and 15A to point 18A, traversing windings 11A and 10A in series to the line 1A again at point 19A; equalizing impedance 16A being parallel to winding 11A, thus neutralizing primary windings 14A and 15A; such input E. M. F. through series primary windings 10A and 11A causing secondary input E. M. F. in one side 20A of the independent load-balancing circuit 4A, through winding 9A, thence through the input transformer 22A to the other line 1, traversing the amplifier.

37 of the independent circuit 4, connecting at 49 and 50 may connect at 51 and 52 instead, for 35 lower potential for use at 37.

54 and 54A are audio transformers connecting tubes 23 and 43A, and 23A and 43. 22 and 22A are audio input transformers connecting the independent load-balancing circuits 4 and 4A with 40 the first audio tubes 23 and 23A from lines 1 and 1A respectively.

55 is the power-pack transformer arrangement; the rectifying tube and associated winding not being shown. X and Y indicate the filament 45 connections between said power pack 55 and audio tubes 23 and 23A, and 43 and 43A; the point of B voltage distribution being shown as 60.

Associated circuits

50 Low-frequency signal and noise-blocking condensers are shown in line 1 and in line 1A at points 48 and 48A.

Assuming that the line currents come in on line 1A and are repeated out to line 1, it will be understood that in grouping elements of the invention that the numerals 6, 32, 9, 13, 33, 37, 38, 40, 41, 42, and 39, indicate an independent load-balancing circuit; that numerals 20A, 32A, 9A, 39A, 3A, 3A, and 40A, indicate an input section 60 of said load-balancing circuit; that numerals 24, 25, 8, 12, 26, 27, 28 and 29, indicate an unbalance-compensating circuit; that 55, 31, 30 and 43, indicate a source of amplified output power; that numerals 2, 10, 11, 14, 15, 16, 45, 46, 47, 17, 18 and 19, indicate a parallel output load-dividing circuit; that numerals 14A, 15A, 45A, 46A, 47A, and 16A, indicate an input E. M. F. neutralizing circuit; that numerals 24, 25, 8, 12, 27, 28, 26, 29, 13 and 21 indicate an input volume control and counter-E. M. F. balancing circuit; that numeral 55 indicates a source of repeater power E. M. F. circuit; that numeral 44 indicates a gain-control circuit; that numerals 22A, 23A, 54A, 44, 43, 30, 31, 60 and 55, indicate an amplifying circuit;

75 that the numeral 48A indicates a line low-fre-

quency signal and noise blocking device; that 1A indicates a line terminal, and that the numeral 22A indicates a primary source of amplifier input.

Assuming that the line currents come in on line 1 and are repeated out to line 1A, it will be understood that the numerals 4A, 32A, 9A, 33A, 37A, 38A, 40A, 41A, 42A, and 39A, indicate an independent load-balancing circuit; that numerals 20, 32, 9, 39, 3, 3 and 40, indicate an input section of said independent load-balancing circuit; that numerals 24A, 25A, 8A, 12A, 26A, 27A, 28A, and 29A, indicate an unbalance-compensating circuit; that numerals 53, 31A, 30A, and 43A, indicate a source of amplified output power; that 2A, 10A, 11A, 14A, 15A, 16A, 45A, 46A, 47A, 17A, 15 34A, and 18A, indicate a parallel output load-dividing circuit; that 14, 15, 45, 46, 47, and 16 indicate an input E. M. F. neutralizing circuit; that numerals 24A, 25A, 8A, 12A, 13A, 21A, 26A, 27A, 28A, and 29A, indicate an input volume-control and counter-E. M. F. balancing circuit; that numeral 55 indicates a source of repeater power E. M. F. circuit; that 44A indicates a gain-control circuit; that 22, 23, 54, 44A, 43A, 30A, 31A, 60 and 55, indicate an amplifying circuit; 25 that numeral 48 indicates a line low-frequency signal and noise blocking device; that 1 indicates a line terminal, and that the numeral 22 indicates a primary source of amplifier input.

Assuming that the line currents come in on 30 line 1, and are repeated out to line 1A, the more essential elements of the invention are the input E. M. F.-neutralizing circuit designated by numerals 14, 15, 45, 11 and 16; the independent load-balancing circuit 4A, 32A, 9A, 13A, 33A, 37A, 38A, 39A, 40A, 41A, and 42A; the parallel output load-dividing circuit 2A, 10A, 11A, 14A, 15A, 16A, 45A, 46A, 47A, 17A, 34A, and 18A; the input volume-control and counter-E. M. F. balancing circuit 25, 29, 8, 12, 13, 21 and 24, and the un- 40 balance compensating circuit 24A. Assuming that the line currents come in on line 1A and are repeated out to line 1, the more essential elements of the invention are the input E. M. F.-neutralizing circuit designated by the numerals 45 14A, 15A, 45A, 11A, and 16A; the independent load-balancing circuit 4, 32, 9, 13, 33, 37, 38, 39, 40, 41 and 42; the parallel output load-dividing circuit 2, 10, 11, 14, 15, 16, 45, 46, 47, 17, 18, and 34; the input volume-control and counter- 50 E. M. F. balancing circuit 25A, 29A, 8A, 12A, 13A, 21A, and 24A, and the unbalance-compensating circuit 24.

Elements such as may be omitted or included as the circumstances and conditions may require, are the vernier balancing circuit indicated by the numerals 37, 38, 49, and 50; the inductance 49; condenser 41; taps 46, 47, 51 and 52, and repeating coil 26.

While the description and drawings illustrate 60 in a general way certain elements and arrangements thereof, which may be employed in carrying the invention into effect, it is obvious that many modifications may be made in the various details without departing from the scope of the 65 appended claims, it being understood that the invention is not restricted to the particular example shown and described.

The invention claimed is:

1. A two-way amplifying self-balancing telephone repeater having at either end a transformer arrangement embodying a balancing bridge circuit of two arms composed of transformer windings in which output currents are equalized, and having a winding of said arrange- 75

ment terminating and connecting between said windings of said two arms, said winding and one of said arms being an input circuit, said winding having differential relation to such equalized 5 output currents; an unbalance compensating circuit having windings differentially associated with said windings in said two arms and thus maintaining equalization of output currents in said arms regardless of impedance fluctuations 10 in one of said arms; an amplifying circuit having output inductive relation to said two arms through other windings of said arrangement; a line terminal connecting to a telephone circuit; and a low frequency signal and noise blocking 15 condenser interposed between said line terminal and said one of said two arms and blocking low frequency noise and signal currents, and passing voice frequencies.

2. A two-way amplifying telephone repeater 20 which when considered from either end of same comprises an independent load balancing circuit having two balancing transformers, an amplifier output transformer and a bridged input circuit transformer and having two identical sections of two windings each, one of which serves as an input section, including said bridged input transformer; an unbalance compensating circuit having one winding each in respective balancing transformers in both of said two sections and 25 which functions without a condenser means and having resistance means and repeating coil means series connected in said unbalance compensating circuit and serving principally as an input volume control and counter line E. M. F. 30 balancing means and serving partially as an unbalance compensating means, having differential secondary relation to output currents in said load balancing circuit through said transformers; a counter line E. M. F. balancing circuit which functions the same as the input volume control means, thus partially balancing input counter line E. M. F. in both sections of said load balancing circuit, thereby partially neutralizing counter output currents which appear 35 as input currents and which are due to irregularities of line impedance; and an amplifying circuit serving to amplify voice currents from one telephone circuit to any telephone circuit associated with the first mentioned telephone 40 circuit, through said telephone repeater.

3. A two-way amplifying telephone repeater 45 which when considered from either end of same comprises two amplifiers, and two sets of balancing transformers interconnected with said amplifiers; a line terminal to which the usual telephone circuit is connected; a line low-frequency signal and noise blocking condenser which passes high frequency voice currents and blocks out low frequency currents, said blocking condenser being 50 interposed between said line terminal and repeater proper; a bridged input transformer; an input transformer having two joined load-dividing circuit windings, one load-balancing circuit winding and one unbalance compensating circuit winding; an input E. M. F. neutralizing transformer having two joined load-dividing circuit windings, one load balancing circuit winding, and one unbalance compensating circuit winding; an output transformer having two primary windings and two secondary load-balancing circuit windings; a high resistance element; a series parallel line output load dividing circuit including said two load-dividing circuit windings of said input transformer, and including 55 said two load-dividing circuit windings of

said input E. M. F. neutralizing transformer, the latter said two windings being parallel connected in said parallel circuit and having non-inductive relation to input currents, one of said two load-dividing circuit windings of said input transformer, being differentially connected to one of said two load-dividing circuit windings of said input E. M. F. neutralizing transformer, said latter two windings having differential relation to output currents and one of said two load-dividing circuit input windings being series connected to said parallel circuit in series relation to the other of said two load-dividing circuit input E. M. F. neutralizing windings, said latter two windings having inductive relation to output currents, said series connected windings being series connected in said telephone circuit and being the secondary output windings in said input transformer and said input E. M. F. neutralizing transformer said two differentially connected windings being neutralized by output E. M. F., one side of the telephone circuit connecting to the junction between said two load-dividing circuit E. M. F. neutralizing windings; an adjustable line impedance series connected between said two series connected secondary output windings; a high resistance element series connected between said differentially connected windings; an independent load balancing circuit having two sections of two windings each 30 which performs the function of balancing said connected bridged input transformer in relation to output currents and neutralizing same to output currents, the primary winding of said bridged input transformer being combined with said load balancing circuit and connecting at the junction between said two load balancing circuit windings in respective sections having primary relation to said two load dividing circuit secondary output windings respectively of said input transformer 40 and said input E. M. F. neutralizing transformer, said later two primary windings having series relation with the other two of said two windings per section; a center tapped inductance series connected between said other two windings of 45 said two windings per section; an amplifying circuit serving to amplify and to repeat voice currents from one telephone circuit to another from said load balancing circuit through said bridged input transformer and through said output 50 transformer to said load balancing circuit, the secondary windings of said output transformer being the other two of said two windings per section and having series relation to said two primary windings of said load balancing circuit, 55 said two secondary windings being series connected through said center tapped inductance, said bridged input transformer primary winding being connected to said center tap; an unbalance compensating circuit, having adjustable impedance series connected with said unbalance compensating circuit winding in said input transformer and with said unbalance compensating circuit winding in said input E. M. F. neutralizing transformer, the unbalance compensating 60 circuit thus having secondary relation in said input transformer and primary relation in said input E. M. F. neutralizing transformer and thus serving to modify characteristic of input currents, to said bridged input transformer through 65 said unbalance compensating circuit and to maintain equalization of output currents in said two sections of said load balancing circuit, said unbalance compensating windings being differentially connected in relation to balanced out- 70 75 80 85 90 95 100 105 110 - put currents through said sections of said load-balancing circuit, output currents flowing through the unbalance compensating circuit when the impedance of one of said sections of 5 said load-balancing circuit is less or more than the impedance in the other of said two sections, the output current thus flowing through said unbalance compensating circuit from one of said sections inducing counter-balancing E. M. F. in 10 the other of said two sections of said load-balancing circuit, the phase and value of such E. M. F. being determined by said adjustable impedance.
4. A repeater for amplification of currents of 15 voice frequency which receives and transmits same at both ends concurrently, said repeater when considered from either end of same embodying an assemblage of transformers comprising an independent output load balancing circuit composed of two sections, having two windings each, one of which sections is an input section including a bridged input circuit common to both of said sections, said input section having a winding through which the telephone line 20 current enters; a parallel line circuit having an input transformer through which it has primary relation to said input section and having an input E. M. F. neutralizing transformer, in which neutralizing transformer input E. M. F. from the 25 said telephone line is neutralized in the other of said two sections of said load balancing circuit, such E. M. F. entering said input section of said load balancing circuit by way of said winding of said input transformer in said input 30 section of said independent load balancing circuit; a parallel line output load dividing circuit having an input transformer and an input neutralizing transformer and including an adjustable line impedance, which serves to equalize 35 said parallel load dividing circuit and thus serves to neutralize input E. M. F. in said neutralizing transformer at one of said two sections and to equally divide output load in both of said input and input neutralizing transformers in said two 40 sections of said load balancing circuit; an input volume control and padding circuit common to both said sections through mutually associated windings in said transformers by which said padding circuit serves to partially balance input 45 current in said load balancing circuit and to partially neutralize said bridged input circuit to input current, said padding circuit being an unbalance compensating circuit common to both said sections through said windings in said input 50 and input neutralizing transformers, and serving also to maintain the balance of the output current in said two sections of said load balancing circuit regardless of impedance fluctuations in the telephone line, reflected in the parallel 55 line load dividing circuit; and an adjustable line impedance said impedance being a load dividing element and an input neutralizing element in said parallel line load dividing circuit.
5. A two-way telephone repeater, which when 60 considered from either end of same comprises a parallel line circuit composed of an input transformer and an input E. M. F. neutralizing transformer; an independent load balancing circuit having two opposite sections of two series windings each, one of which sections includes a secondary winding of said input transformer, said one section serving as an input circuit and including one of two primary windings of a bridged input circuit transformer, said winding being common to both said sections; an inductance 65 means series connected in said load balancing circuit and having a center-tap connection forming one terminal of said bridged input circuit transformer primary winding; a vernier balancing resistance having a variable center tap forming one terminal of the second one of said two primary windings of said bridged input circuit transformer and having series parallel relation to said independent load balancing circuit, said vernier balancing resistance and second primary 70 winding functioning as a close balancing means with reference to said bridged input circuit transformer having two primary windings, the counterbalancing output E. M. F. of one of said two windings being controlled by said vernier resistance; a parallel line output load dividing circuit including series dividing resistance and having secondary relation to said load balancing circuit through windings of said input transformer in one of said two sections and through windings of said input E. M. F. neutralizing transformer in the other of said two sections, the line impedance reflected in the line windings of said load dividing circuit being thus equalized in associated windings of said transformers in said 75 two opposite sections of said load balancing circuit, thus balancing said bridged input circuit transformer in relation to output E. M. F. through said two sections; an input volume control circuit having a series resistance means, said volume control circuit being common to both said two sections and having secondary relation in said input transformer and primary relation in said input E. M. F. neutralizing transformer which thus functions to partially balance said bridged input circuit transformer to input current by partially equalizing input currents in said opposite sections of said load balancing circuit by said series resistance means, such input currents being in the same direction in both said sections, said load balancing circuit, said input volume control circuit and said load dividing circuit all being inductively connected through respective windings in said input transformer and in said input E. M. F. neutralizing transformer, in said two opposite sections.
6. A two-way telephone repeater, which when considered from either end of same embodies an assemblage of interconnected transformers, an amplifier output transformer, an input transformer, an input E. M. F. neutralizing transformer and a bridged input circuit transformer, and comprises an independent load balancing circuit having a center tapped inductance means of load balancing circuit resistance control, and including said bridged input circuit transformer and comprising two opposite sections of two windings each, including secondary windings of said amplifier output transformer, one of which two identical sections being an input section having a secondary winding of said input transformer and including one primary winding of said bridged input circuit transformer, the other of which two sections having a secondary winding of said input E. M. F. neutralizing transformer and in both of which sections output currents are equalized, said input and said input E. M. F. neutralizing transformers serving also as output transformers; a parallel line output load dividing circuit comprising two non-inductively connected primary windings of said input E. M. F. neutralizing transformer and two series connected primary windings of said input transformer, said parallel line output load dividing circuit including an adjustable line impedance between said 75

transformers, said load dividing circuit serving to neutralize input current in one section of said load balancing circuit and to equally divide output impedance in both sections of said load balancing circuit through said input and said input 5 E. M. F. neutralizing transformers; an input volume control circuit having a variable resistance and having a secondary winding in said input transformer and a primary winding in said input 10 output E. M. F. neutralizing transformer and which functions to partially equalize input currents in both sections of said load balancing circuit, input currents thus passing from the input section to the other of said two sections through said input 15 volume control circuit, thus partially reducing input volume, by partially balancing said bridged input circuit transformer to said input currents in the same direction in both said sections.

7. A two-way telephone repeater which when 20 considered from either end of same comprises an independent load balancing circuit of two sections, one of which is an input section, each section having a primary output winding which is also a secondary input winding, said windings having a bridging condenser means, said condenser means serving as an output control shunt 25 controlling output volume and frequency characteristic, said condenser means also serving as an impedance element to control load balancing circuit operating impedance independently of line 30 impedance; a parallel output load dividing circuit having windings secondary to said load balancing circuit primary windings; an adjustable line dividing impedance series connected between 35 said secondary windings, and serving to equalize line impedance in said primary windings of said load balancing circuit through said secondary windings of said load dividing circuit, said secondary windings being series connected in the 40 line on opposite sides of said dividing impedance; an input E. M. F. neutralizing transformer having two non-inductively connected primary line windings which neutralize input E. M. F. in said 45 secondary input winding in one section of said load balancing circuit; an input transformer having two series parallel connected primary line windings which inductively induce input E. M. F. in said secondary winding in the other section of 50 said load balancing circuit serving as the input section; and an input volume control circuit having variable impedance elements and having series windings secondary to both said sections and serving to control the volume of input E. M. F. in said input section of said load balancing circuit, by introducing input E. M. F. in the other 55 of said two sections from said input section through said input volume control circuit.

8. A duplex telephone repeater which when considered from either end of same consists of two 60 amplifiers; an input and an output arrangement of transformers associated with said two amplifiers in such manner that the amplifier in one direction does not interfere with the amplifier in the other direction; a parallel output load dividing circuit; a source of amplified output power, consisting of a conventional arrangement of amplifying valves and transformers; an independent load balancing circuit having two sections of two windings each and having variable 65 balancing resistance common to both sections, and being interposed between said amplified output power source and said parallel output load dividing circuit, the repeater balancing impedance being thus controlled independently of line impedance; a parallel line output load dividing cir- 70

cuit having an input E. M. F. neutralizing transformer, an input transformer, and an adjustable output load dividing impedance interposed and series connected between secondary output windings of said transformers, and serving to admit 5 input current to one section of said load balancing circuit and to exclude input current from the other section, said input transformer having inductive relation to one section and said input E. M. F. neutralizing transformer having non-inductive relation to the other of said sections, and serving to equalize output current in respective primary windings of said two sections of said load balancing circuit associated with said two series connected secondary output windings, 15 both said transformers having inductive relation to respective ones of said sections, one side of said parallel line output load-dividing circuit including a tapped inductance means comprising one secondary winding each of said transformers, and 20 which as an impedance element, serves as a semi-self balancing means, confining variations of line impedance to the other respective secondary windings of said transformers comprising said load dividing means, which thus functions to minimize 25 repeater unbalance due to changes in line impedance; a high resistance means in said side of said parallel output load dividing circuit to be used at will, in lieu of said inductance means and serving to minimize repeater unbalance due to 30 change in line impedance; an input volume control and padding circuit which serves also as an unbalance compensating circuit in connection with said load balancing circuit, and having inductive relation to said two sections through associated primary and secondary windings of said 35 two transformers.

9. A two-way telephone repeater which when considered from either end of same consists of an interconnected set of transformers comprising a 40 bridged input circuit transformer primary winding; an independent load balancing circuit of two identical sections of two windings each, including an amplifier secondary output winding and a load balancing circuit primary output 45 winding, said sections having parallel bridging connection to said input circuit transformer primary winding, said section windings being series connected; a parallel line output load dividing circuit having an adjustable line 50 dividing impedance, an input transformer having two secondary windings, and an input E. M. F. neutralizing transformer having two secondary windings; a high resistance means combined with one side of said parallel circuit restricting reflections of line impedance to the other side including dividing impedance; an unbalance compensating circuit including series connected variable impedance units which functions to neutralize excess output E. M. F. in either section of said load balancing circuit at low impedance with output E. M. F. from the other section of said load balancing circuit at high impedance, thus maintaining repeater balance regardless of impedance changes in either section 65 of said load balancing circuit due to impedance change in the telephone line which becomes effective in said primary windings of said load balancing circuit through said secondary windings of said load dividing circuit, said unbalance compensating circuit having windings secondary to both said sections; an input volume control circuit combined with said unbalance compensating circuit, serving to partially balance input currents in both sections of said load balancing circuit, 75

thus partially balancing said bridged input circuit transformer primary winding.

10. A two-way amplifying telephone repeater which when considered from either end of same comprises an independent load balancing circuit having an associated unbalance compensating circuit, a multiple connected vernier balancing circuit, a shunt condenser impedance control means, a series connected center tapped inductance multiple connected with said condenser means, an input section and another section; an amplifying circuit which amplifies voice currents, said amplifying circuit comprising a source of amplified output power, and a parallel line output load dividing circuit having two balancing transformers between which circuits said load balancing circuit is interposed; a source of repeater power E. M. F. circuit which actuates said amplifying circuit in its voice current amplifying function; a calibrated gain control circuit which determines the degree of amplification of said voice currents through said amplifying circuit; a parallel input E. M. F. neutralizing circuit and a series parallel input circuit which are component parts of said parallel load dividing circuit functioning to inductively neutralize input currents in one of said two transformers at one section of said load balancing circuit, and functioning to admit input current through the other of said two transformers into the other one of said sections; a primary source of line input comprising the usual associated telephone circuit; a line terminal at which said telephone circuit is connected to the repeater, and a line low frequency signal and noise blocking device effecting high resistance to low frequencies and low resistance to high frequencies, said device being series connected at said line terminal.

11. A two-way amplifying telephone repeater which when considered from either end of same embodies an assemblage of balancing transformers comprising an independent load balancing circuit of two opposite sections one of which is an input section, having an amplifier output transformer and two balancing transformers, each of said two opposite sections including one winding of said output transformer and one winding respectively of said two balancing transformers, said windings of said output transformer being series connected to both said windings of said two balancing transformers, respectively; a shunt condenser means for circuit impedance control and another shunt condenser means for output volume control and characteristic modification, multiple connected to both said windings of said two balancing transformers; a vernier balancing element, multiple connected to both said windings of said balancing transformers and said shunt condenser in said independent load balancing circuit; an inductance means, which, being in multiple connection with first one of said condenser means, determines load balancing circuit impedance, independently of telephone line impedance, said inductance means being center tapped and series connected between both said windings of said output transformer, the center-tapped point of said inductance means intersecting both said sections; an unbalance compensating circuit having variable impedance and having secondary relation to both said sections through respective windings of said two balancing transformers which compensating circuit automatically maintains equalization of output currents in both said two sections regardless of reflected fluctuations of line impedance in one

of said sections thus maintaining repeater balance, a parallel line output load dividing circuit having an adjustable line dividing impedance and having secondary relation to both sections of said load balancing circuit through said balancing transformers causing said two balancing transformers to function also as an input E. M. F. neutralizing transformer and an input transformer respectively, said parallel load dividing circuit admitting input currents to one of said two sections and excluding input currents from the other of said two sections of said load balancing circuit, and to equalize output line impedance in said opposite sections of said load balancing circuit; a source of amplified output power comprising a two stage amplifying circuit having two tubes and two transformers, and having primary relation to said load balancing circuit through said output transformer; a calibrated gain control circuit, associated with said amplifying circuit, and serving to control amplification; and a line terminal at which the usual telephone circuit is connected to the repeater.

12. A two-way amplifying telephone repeater which when considered from either end of same includes a telephone line circuit; an independent load balancing circuit having an input section and another section, said input section including a bridged amplifier input transformer, and having a center tapped inductance means serving to determine the operating resistance of said load balancing circuit; an amplifying circuit comprising two matching transformers with two associated amplifying tubes and including a calibrated gain control, said amplifying circuit being interposed between said input section and said load balancing circuit at opposite ends of said telephone repeater; an unbalance compensating circuit having adjustable impedance, said compensating circuit having secondary relation with said sections and functioning with said load balancing circuit as a filter circuit to determine the voltage frequency characteristic of input currents to said input section of said load balancing circuit, thus characterizing input currents to said amplifying circuit; two balancing transformers; a parallel output load dividing circuit including two joined windings each of said two balancing transformers and having an adjustable line impedance means series connected in one side of said parallel output load-dividing circuit, said parallel circuit thus comprising four windings, one side of said telephone line circuit connecting to one of said transformers at the junction between two of said joined windings, said two windings having parallel and non-inductive relation to input currents from said telephone line circuit, thus being neutralized by input current, said adjustable line impedance means connecting at the junction between two of said joined windings of the other of said transformers, the line circuit thus passing through one winding of one transformer at one section, through said dividing impedance, through one winding of the other of said transformers at the other said section to the other side of said telephone line, the other two windings of said transformers respectively being connected together to form a circuit parallel thereto, and having differential relation to output currents; and a line low frequency signal and noise blocking device series connected in said telephone line circuit and serving to exclude low frequency currents from, and to admit high frequency currents to the telephone repeater.

13. A two-way amplifying telephone repeater consisting of transformer connected circuits which when considered from either end of same comprises a differentially connected unbalance compensating circuit having a series connected adjustable impedance; an independent load balancing circuit having two sections including an input section, and having a bridged amplifier input transformer connected common to both sections, one of which sections functions as an input section in relation to said unbalance compensating circuit in conjunction with said adjustable impedance, said compensating circuit having low resistance, the other of which sections functions as the input section in relation to said unbalance compensating circuit having comparatively high resistance, said unbalance compensating circuit having series connected windings associated with both said sections; a parallel line output load dividing circuit having inductive relation to said load balancing circuit and comprising an input section having an input transformer and an input neutralizing section having an input E. M. F. neutralizing transformer, and serving to admit input currents of low potential to one section only of said load balancing circuit through said input transformer and to admit input currents to one winding only of said unbalance compensating circuit, in said input transformer; providing a low resistance input filter circuit through which circuit input currents of high potential from said input transformer pass to said input section of said load balancing circuit, an amplifying circuit, the characteristic of whose amplified currents is determined by the characteristic of said unbalance compensating circuit; a source of repeater power E. M. F. circuit which is connected to and actuates said amplifying circuit; a source of line input connected to and from which input currents enter said parallel load dividing circuit; and a line terminal at which the telephone circuit comprising said source of line input, is connected to the repeater.

14. A two-way amplifying and self balancing telephone repeater which when considered from either end of same comprises a primary source of line input, which, in either direction, comprises the usual associated telephone circuit; a line terminal at which the telephone circuit is connected to the repeater; a line low frequency signal and noise blocking device interposed between said terminal and the repeater; an input E. M. F. neutralizing transformer; an input transformer having a winding joined to a winding of said neutralizing transformer; an output transformer; a center tapped inductance and a bridged input circuit transformer connected to said center tap and to the junction between said two joined windings; an independent load balancing circuit having two sections one of which serves as an input section, and simulating a bridge having two arms, one arm including a winding of said input transformer, the other arm including a winding of said input neutralizing transformer, each arm including a winding of said output transformer, both arms being connected together between said two joined windings and through said center tapped inductance; an unbalance compensating circuit serving as an automatic balancing circuit and as an input volume control and characterizing circuit inductively connected to said load balancing circuit through differentially connected windings at both said sections in said input and input neutralizing transformers, and serving to automatically balance output currents in said two

sections; an amplifying circuit inductively connected to said load balancing circuit through said output transformer and transmitting amplified alternating currents to same; a parallel output load dividing circuit having inductive connection to said load balancing and said unbalance compensating circuits through said input and input neutralizing transformers, causing input currents from one telephone circuit which traverse said line terminal and said low frequency blocking device to traverse said input neutralizing transformer of said load dividing circuit, said input transformer of said load balancing circuit, said unbalance compensating circuit, causing said unbalance compensating circuit to function as an input volume control and characterizing circuit, said input section, said bridged input circuit transformer, said amplifying circuit, said load balancing circuit inductively connected to said unbalance compensating circuit, causing said unbalance compensating circuit to function as an unbalance compensating circuit, said parallel line output load dividing circuit, said line low frequency signal and noise blocking device, said line terminal to the other associated telephone circuit.

15. A two-way self balanced telephone repeater which when considered from either end of same comprises a primary source of line input consisting of conventional telephone circuits; line low frequency signal and noise blocking condensers series connected in said telephone circuits and with said source, and serving to block out low frequency currents from said source; an output transformer; an input E. M. F. neutralizing transformer having two parallel connected line windings series connected with said source and inductively neutralizing input currents from said source, in said parallel connected windings; an input transformer having two series parallel connected line windings in which input currents are inductive; an amplifier input transformer; an input circuit having a winding in said amplifier input transformer series connected with a winding in said input E. M. F. neutralizing transformer through which circuit input currents are thus admitted to said amplifier input transformer; an unbalance compensating circuit having variable impedance elements series connected and serving as an input characterizing circuit, said unbalance compensating circuit having windings in said input and input E. M. F. neutralizing transformers and through which input currents pass from said input transformer to said input circuit in said input E. M. F. neutralizing transformer; an independent load balancing circuit having two sections including an input section which includes said amplifier input transformer, said two sections being inductively connected respectively with said unbalance compensating circuit through said input transformer and through said input E. M. F. neutralizing transformer; an amplifying circuit having inductive connection to said independent load balancing circuit through said amplifier input transformer and having a calibrated gain control, indicating gain in decibels; an independent load balancing circuit having inductive connection to said amplifying circuit through said output transformer and having two sections of two windings each in which amplified output currents are equalized, said amplifier input transformer intersecting and being bridged across said two sections; an unbalance compensating circuit having variable impedance elements series connected and

- having inductive connection to said two sections through respective windings in said input and input E. M. F. neutralizing transformers and automatically maintaining balance of output currents in said two sections; a parallel line output load dividing circuit having inductive relation to said two sections through windings in said input transformer and in said input E. M. F. neutralizing transformer which equalizes output line impedance in said two sections of said load balancing circuit through mutually associated windings in said transformers; and a line terminal through which telephone repeater input currents from said primary source of input, traverse said line 5 low frequency signal and noise blocking condenser, said input E. M. F. neutralizing transformer, said input transformer, said unbalance compensating and characterizing circuit, said input section of said load balancing circuit, said 10 amplifying circuit, said independent load balancing circuit, said parallel load dividing circuit, said line low frequency signal and noise blocking condenser, and said line terminal.
16. A bi-path amplifying telephone repeater which when considered from either end of same comprises the following elements in its function of repeating and amplifying alternating currents from a primary circuit to a secondary circuit in both directions concurrently, and in preventing 15 said amplified currents from returning to the respective primary circuit; a line terminal connected with each of said circuits; a line low frequency signal and noise blocking condenser series connected in each of said circuits and serving to block out low frequency signal and noise currents from said associated circuits; a parallel line input E. M. F. neutralizing transformer connected to each of said circuits and inductively neutralized by input currents from said circuits; an input 20 transformer series parallel connected to each of said input E. M. F. neutralizing transformers through which input currents are inductively admitted to the repeater; a variable divided impedance; a parallel-line output load-dividing circuit embodying said input E. M. F. neutralizing transformer, said input transformer and said variable divider impedance; a bridged amplifier input transformer; an independent load balancing circuit embodying said bridged amplifier input transformer and having two sections, one of which serves as an input section associated with said input transformer of said load-dividing circuit, the other section being associated with said input E. M. F. neutralizing transformer of said 25 load dividing circuit; an unbalance compensating circuit having inductive connection with said two sections through said input and input E. M. F. neutralizing transformers and serving principally as an input volume control and a counter E. M. F. balancing circuit, for conditions not requiring unbalance compensating, and having series connected resistance control; an output transformer; an amplifying circuit inductively connected to said load balancing circuit through said output 30 transformer and serving to amplify and repeat voice currents from said input section through said bridged input transformer of said load balancing circuit; and a calibrated gain control connected in said amplifying circuit determining degree of amplification in decibels, said calibrated element being combined with said amplifying circuit, in a manner to control E. M. F. of amplified currents.
17. A two-way amplifying telephone repeater embodying an assemblage of interconnected 35 transformers and which when considered from either end of same comprises a line terminal to which the telephone circuit is connected; a line divider-impedance; a variable high resistance means; a line low frequency signal and noise blocking condenser through which amplified voice currents are transmitted, from the repeater to said telephone circuit, but which serves to block out amplified currents of signal and noise frequency; an input transformer; an input E. M. F. 40 neutralizing transformer; an output transformer; a parallel line output load dividing circuit having said adjustable line divider-impedance and having two joined windings of said input transformer and two joined windings of said input E. M. F. neutralizing transformer, the four windings being series parallel connected to the line at the junction between said two joined windings of said input E. M. F. neutralizing transformer, one winding of each of said two windings in said transformers 45 being series connected to the line at the terminal of one of said two windings of said input transformer, with said divider impedance series interposed between said windings, and one winding each of said two windings in said transformers 50 being series connected with said variable high resistance means, said one winding each and said high resistance forming a circuit parallel to said divider resistance and said one winding in said input E. M. F. neutralizing transformer, and connecting series parallel at the junction between said two joined windings of said input transformer of said output load dividing circuit; a bridged input circuit transformer; an independent load balancing circuit having two sections of one winding 55 each of said input transformer and said input E. M. F. neutralizing transformer and having a winding of said bridged input circuit transformer connected to and intersecting both said sections, one of said sections serving as an input section, 60 amplified output currents being transmitted to said windings of said parallel-line output load-dividing circuit through said windings of said two transformers in said two sections; a source of amplified output power having two inequality 65 matching transformers and said output transformer, comprising an amplifying circuit, having an output tube and an input tube, and which transmits amplified voice currents to said load balancing circuit, the two amplifying tubes of said 70 amplifying circuit being connected by one of said inequality transformers, the output tube being connected to said load balancing circuit through said output transformer having a winding in each of said two sections, said input tube being connected to said input section through a secondary winding of said bridged input circuit transformer, bridged across said load balancing circuit; two variable impedance elements; an unbalance compensating circuit having a winding in said input transformer and a winding in said input E. M. F. 75 neutralizing transformer series connected with said two variable impedance elements through which input currents are modified in characteristic, in passing from said input transformer to said input section of said load balancing circuit.
18. A two-way amplifying self-balancing telephone repeater consisting of two arrangements of bridged input circuit inequality transformers, output transformers and balancing transformers interconnected with two amplifiers, which when considered from either end of same comprises an independent load balancing circuit having two sections of two windings each, one of which serves 80
- 75

as an input section which includes such bridged input circuit inequality transformer connected to and common to both such sections, such transformer comprising a high impedance secondary 5 winding and a center tapped two winding primary of low impedance, one winding serving as the bridged input element; a high resistance potentiometer having a variable center tap; a vernier balancing circuit series parallel connected to such 10 load balancing circuit and including two windings of such output transformer and including said series high resistance potentiometer having a variable center tap and including one winding of such center tapped primary of such input circuit in- 15 equality transformer, said one winding of such center tapped primary being differentially related to the other primary winding and serving to closely balance said bridged input circuit transformer in relation to output currents through said two 20 sections, thus neutralizing said input circuit transformer to output currents, said vernier circuit winding being connected to said vernier circuit through said potentiometer center tap; a series parallel-line output load-dividing circuit 25 having series connected variable dividing-impedance and having two windings of one of such balancing transformers inductively connected to one of said two sections through one of said two windings per section, and having two windings of the 30 other of said balancing transformers inductively connected to said input section through one of said two windings per section, which load dividing circuit functions to equalize output load in said two sections of said independent load balancing circuit, through such balancing transformers, one winding each of said two windings per transformer being series connected with the telephone circuit, said dividing-impedance being interposed 35 between said series connected windings, one winding each of said two windings being differentially connected and forming a parallel circuit, said parallel circuits being series connected to one of said two windings in one of said balancing transformers at said input section, said series parallel 40 circuit having series parallel connection to the telephone circuit; an amplifying circuit having two amplifying tubes and being inductively connected to said load balancing circuit through one of said two windings per section in said output 45 transformer; a conventional A. C. power supply line; a source of repeater power E. M. F. circuit having a transformer with different windings, one of which is a primary winding, connected to said supply line; a rectifying tube and a filter, converting said A. C. power to D. C. power, said D. C. power being of high E. M. F. and supplying operating E. M. F. to said amplifying circuit, and having two windings supplying A. C. filament voltage for said amplifying tubes, one A. C. winding sup- 50 plying the filament of said rectifying tube, one power winding delivering said D. C. voltage through said rectifying tube to said filter, said filament and power windings being inductively connected to said conventional A. C. power supply line through said primary winding, said power E. M. F. circuit also including series connected grid-bias resistances in plate circuits of said amplifying tubes.

19. A two-way amplifying telephone repeater 55 which when considered from either end of same comprises a bridged input circuit transformer; a variable center tapped inductance; an independent load balancing circuit having two sections connected to said bridged input transformer and including said variable center tapped inductance,

by means of which circuit said bridged input circuit transformer is balanced independently of line impedance; an input transformer; an input E. M. F. neutralizing transformer; a parallel line output load dividing circuit dispensing with an 5 artificial balancing line, including said input E. M. F. neutralizing transformer and including said input transformer and being inductively connected to said two sections through said trans- 10 formers, and serving to equally divide output load in primary windings in said balancing circuit sections; an adjustable line-impedance in one side of said parallel line output load dividing circuit which serves as a series line-impedance divider, and thus equalizing line-impedance in secondary 15 windings of said transformers respectively, in said two sections, said windings having series connection in opposite sides of the telephone line at said two sections; a line terminal to which a telephone circuit is connected; a line low frequency signal and noise blocking condenser interposed between said line terminal and said parallel load-dividing circuit, said blocking device passing high frequency currents and blocking low frequency currents; an output transformer; an 20 amplifying circuit having inductive connection to said load balancing circuit through said output transformer and through said bridged input circuit transformer and serving to amplify and to repeat voice currents from one telephone circuit to another telephone circuit; an unbalance compensating circuit inductively connected to said two sections of said load-balancing circuit through respective windings of said input transformer and said input E. M. F. neutralizing transformer, said 25 unbalance compensating circuit compensating changing line impedance reflected in said input transformer in one of said two sections, thus maintaining equalization of output currents in said two sections of said load balancing circuit 30 thus connected; a high resistance unbalance minimizing unit connected in one side of said parallel line output load dividing circuit, restricting line impedance reflections to the parallel load dividing side; and a vernier balancing circuit 35 parallel connected to said load balancing circuit and having a differentially connected primary winding in said bridged input transformer and serving as a close balancing means in said load balancing circuit.

20. A two-way amplifying self-balancing telephone repeater which when considered from either end of same comprises a line terminal at which the repeater terminates; a line low frequency signal and noise blocking condenser interposed between said terminal and the repeater; a series parallel line output load dividing circuit having an input transformer and an input E. M. F. neutralizing transformer in separate sections serving to equally divide line load in said separate sections, one of said separate sections serving as an input section, input current being neutralized inductively in the other of said sections, the equalization of output currents in said separate sections also balancing and neutralizing one side of 45 said parallel line circuit to output currents; an unbalance compensating circuit having inductive relation to both of said sections through associated series connected windings in said transformers and serving as characterizing entrance circuit for 50 input currents from said input section of said load dividing circuit; and serving also to equalize output currents in said separate sections of said load dividing circuit; a center tapped inductance; an independent load balancing circuit having op- 55

tional impedance and having two sections, one section including a winding of said input E. M. F. neutralizing transformer and serving as an input section, the other section including a winding of 5 said input transformer, said sections having connected a bridged input circuit transformer, said independent circuit comprising an intermediate balancing circuit, not an artificial line, for the purpose of repeater balance, independently of 10 line impedance, by means of said center tapped inductance, and having inductively associated said unbalance compensating circuit by means of which output currents in said load balancing circuit are automatically equalized in said sections 15 and in said separate sections of said parallel line output load dividing circuit.

21. A two-way amplifying telephone repeater which in amplifying and repeating voice currents from one repeater associated telephone circuit to 20 another repeater associated telephone circuit, prevents the return of amplified currents to the input telephone circuit, without artificial-line circuit balancing means, said repeater having a plurality of circuits inductively connected with each 25 other, said repeater when considered from either end of same embodying a plurality of interconnected balancing transformers, said balancing transformers including said circuits, said repeater comprising a line terminal interposed between 30 each associated telephone circuit and one of said circuits; a line low frequency signal and noise blocking condenser device serving to block low frequency current and to pass high frequency current, and being interposed between said line terminal and one of said circuits; an amplifying 35 circuit having an input transformer with bridged input circuit windings, and an output transformer; a parallel-line output load-dividing circuit; an independent load balancing circuit of two 40 arms and having secondary relation to said amplifying circuit through said output transformer and including said bridged windings of said input transformer, said load balancing circuit having primary relation to said load dividing 45 circuit through certain of said plurality of load-balancing transformers; an unbalance compensating circuit having secondary relation to said load-balancing circuit through certain of said plurality of load-balancing transformers, said unbalance compensating circuit preventing unbalance 50 of output currents in said load-balancing circuit arms, due to fluctuations of line load in said load dividing circuit; and a source of repeater power E. M. F. circuit associated with said amplifying circuit, and actuating same.

22. A balanced two-way, self-compensating, telephone repeater which when considered from either end of same includes a balancing bridge of two arms having transformer windings; an input 60 circuit having a winding connected to and centrally intersecting said arms; an adjustable impedance; an amplifier output circuit having windings associated with said arms; a line input circuit composed of transformer windings associated 65 with one of said arms; a line balancing circuit having windings associated with said bridge and equalizing the output impedance of said arms, said line balancing circuit including said adjustable impedance; an amplifying circuit having a winding 70 associated with said input circuit winding connected to said arm; an unbalance compensat-

ing circuit having differentially connected windings associated with said windings in said arms.

23. A two-way telephone repeater which when considered at either end of same includes inductively related circuits comprising an automatically counter-balanced input-output balancing bridge of two arms which incorporate an output load-balancing circuit having transformer windings; an amplifier output circuit having inductive relation to said load-balancing circuit through 10 transformer windings associated with said arms; an unbalance compensating circuit having differential relation to said output load-balancing circuit through said transformer windings of said arms and counter-balancing same; an amplifier 15 input transformer winding having abridged relation to said output load-balancing circuit arms; a line-balancing circuit including an adjustable impedance and having inductive relation to said load-balancing circuit through said transformer 20 windings in said arms and equalizing output impedance of same; a line input circuit having non-inductive relation to said load-balancing circuit and said unbalance compensating circuit through said transformer windings in one of said arms, 25 and having inductive relation to said load-balancing circuit and said unbalance compensating circuit through said transformer windings in the other of said two arms; and an amplifying circuit associated with said amplifier input transformer 30 winding.

24. A two-way telephone repeater, which in considering either end of same, comprises a bridge of two arms having primary and secondary transformer windings and forming a load-balancing 35 circuit which includes two arms; an amplifier input winding having bridged relation to said arms; a bridged vernier balancing input winding having differential relation to said amplifier input winding; an amplifier output circuit having primary 40 windings associated with said arms; a line input circuit having differential windings associated with one of said arms and having inductive windings associated with the other of said arms; a line-balancing circuit including an adjustable 45 impedance and having inductive windings associated with both of said arms and equalizing output impedance of same; an amplifying circuit associated with said bridged amplifier input winding and said vernier winding. 50

25. A balanced two-way, self-compensating, telephone repeater which when considered from either end of same includes a balancing bridge circuit of two arms having transformer windings; and including an input circuit having a winding 55 connected to and centrally intersecting said arms; an adjustable impedance; an amplifier output circuit having windings associated with said arms; a line input circuit forming part of said balancing bridge circuit composed of transformer windings 60 associated with one of said arms; a line balancing circuit having windings associated with said bridge circuit and equalizing the output impedance of said arms, said line balancing circuit including said adjustable impedance; an amplifying 65 circuit having a winding associated with said input circuit winding and an unbalance compensating circuit having differentially connected windings associated with said windings in said arms. 70
